UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

BOOT AND SHOE BOTTOM.

Application filed January 25, 1918, Serial No. 543,089. Renewed March 11, 1922.

To all whom it may concern:

Be it known that I, ERASTUS E. WINKLEY, a citizen of the United States, residing at Lynn, in the county of Essex and State of Massachusetts, have invented certain new and useful Improvements in Boot and Shoe Bottoms; and I do hereby declare the following to be a full, clear, and exact description of the invention, such as will enable others skilled in the art to which it appertains to make and use the same.

This invention relates to boots and shoes, and particularly to that part of a boot or shoe which includes the out sole and heel and is commonly designated as the "bottom."

In the prior art certain styles of boots and shoes have embodied outsoles comprising a short sole and a heel-seat portion in abutting relation, and to which the heel is attached. The short sole is of a good grade of sole leather and is of the usual form and character from the toe to substantially the rear end of the shank-portion. The heel-seat portion is of leather of an inferior character and is of such form as to make, in conjunction with the short sole, an outsole of the commonly employed contour. By this expedient, a material saving of expensive leather is effected, while the inferior and cheaper leather of the heel-seat portion possesses the necessary characteristics to enable it to take a satisfactory randing cut, a key-wheel marking, and ultimate finish or polish.

One of the objects of the present invention is to effect further economies in leather and in the expense of manufacture of boots and shoes, and to provide a relatively cheap boot or shoe bottom that shall possess the usual wearing qualities and shall embody a clean-shaped, smooth and durable randing, a distinct and permanent beading or key-wheel marking, and a satisfactory ultimate finish or polish that shall compare favorably with that of the boot or shoe bottoms of the prior art.

One feature of the present invention resides in the employment of a heel-seat portion of ordinary commercial leatherboard or other analogous leather or paper composition which has been subsequently treated and compressed. This leatherboard heel-seat portion is preferably prepared in the

general manner set forth and claimed in a copending application Serial No. 213,681, filed Jan. 25, 1918, by the present applicant, and, by reason of its preparation, its surface, initially unsuited for applicant's purpose, acquires to an appreciable depth, the above-mentioned beneficial, desirable and improved properties that render it capable of satisfactory use in the manufacture of shoe bottoms.

Another feature of the present invention resides in the use of a heel-seat portion and a heel of commercial leatherboard that are initially treated and compressed to final size and form, and which are positioned in registry the one with the other so that no further trimming is requisite, whereby the beneficial surface characteristics thereof are retained to facilitate and render specially effective the subsequent finishing operations.

Other objects of the invention and features by which they are attained will become apparent from the following description in connection with the illustrated preferred embodiment of the invention.

Throughout the specification and claims the term "leatherboard" is used in a generic sense to include any of the cheaper and analogous grades of ordinary commercial heel-stock material of leather, paper or other suitable compositions, the properties and characteristics of which are unsuited for the present purposes.

The invention will be most readily understood by a reference to the accompanying drawing which illustrates the preferred embodiment of the invention, in which Figure 1 is a plan-view of a two-piece boot or shoe outsole embodying the invention; Fig. 2 is a view in side elevation of the outsole illustrated in Fig. 1; and Fig. 3 is a view in side elevation of a shoe having a bottom comprising a two-piece outsole to which a heel of final size and form is attached.

Referring to the drawing, a boot or shoe outsole 10 comprises a short sole 12 of a good grade of leather, and a heel-seat portion 14 of leatherboard or other analogous material which has been treated and compressed in the manner above indicated. The short sole 12 is of the ordinary form from the toe to substantially the rear end of the shank portion, which end is scarfed in order that it may be placed in abutting relation to a simi-

larly beveled end of the treated and compressed leatherboard heel-seat portion 14, the two component members being preferably united together by staples, or other 5 suitable means, to constitute a unitary outsole that may be attached to a lasted shoe in accordance with customary practice.

The heel-seat portion 14 is composed of the usual commercial leatherboard that has 10 been shaped, treated and subsequently compressed and condensed in the general manner set forth in the above mentioned copending application. More specifically, the heel-seat portion 14 is dinked or otherwise 15 formed to definite shape from a sheet or piece of ordinary leatherboard, after which a randing 15 is cut around the upper edge thereof and its surface, and particularly its edges, are then filled with a suitable sizing 20 material that penetrates the surface to an appreciable depth. The sizing is then permitted to dry to a greater or less extent, and the shaped and treated heel-seat portion is then placed in a mould and heavily compressed 25 to its final size and form. This treatment and subsequent compression results in condensing and compacting the leatherboard and producing an impregnated surface of appreciable depth that is smooth, 30 hard, and durable, and particularly adapted to take a permanent and distinct key-wheel marking, and a superior, ultimate finish or polish. The surface qualities of the initial leatherboard are thus improved and modified 35 and rendered adaptable for the purpose intended.

The dinking and rand-cutting of the heel-seat portion to definite shape is of particular importance, for the reason that the shaped heel-seat portion is adapted to closely fit 40 within the mould throughout its entire surface, whereby the pressure to which it is subjected is uniformly distributed, thus resulting in a more uniformly consolidated 45 and condensed article. Moreover, the dinking and rand-cutting operations roughen the edges and open the pores thereof, so that the penetration of the sizing material is facilitated and rendered especially effective.

50 The sizing or filling step is also of importance, in that the sizing material penetrates the pores and serves to raise or turn out the exposed fibres which are subsequently turned in and compacted to form a surface having 55 improved and modified characteristics and properties which materially aid and contribute to the durability and subsequent finish of the article.

After the two-piece outsole has been attached 60 to the lasted shoe in any well-known manner, a treated and compressed leatherboard heel 16 of final size and form, such as is produced by the method set forth in the above-mentioned copending application, is 65 positioned in registry with the treated and

condensed heel-seat portion 14 and secured in position in any suitable manner. The relative proportions of the component parts of the bottom are so chosen that the heel when positioned upon the shoe overlaps the 70 short sole 12 and thus covers the joint between it and the heel-seat portion 14.

A leather top-lift 18 is then attached and the completed heel comprising the treated and compressed leatherboard heel-seat portion 14, heel 16, and leather top-lift 18, are 75 lightly scoured, and the subsequent ordinary finishing operations, including the beading or key-wheel marking, are performed.

By reason of the fact that the heel-seat 80 portion 14 and heel 16 are initially made to final size and form and are positioned in registry the one with the other, no further trimming thereof is necessary, and a light scouring is sufficient to remove any slight 85 roughness or protuberances, so that the surface is not removed and the beneficial qualities of the improved and modified lateral surfaces are retained to improve the ultimate 90 finish and facilitate the finishing operations. 95 Moreover, these qualities lend themselves toward a smooth and clean-shaped randing, and a distinct and permanent key-wheel marking, all of which contribute to a finished heel that compares favorably in durability, appearance and finish with those of the prior art that have embodied heel-seat portions of leather in lieu of relatively cheap leatherboard material.

Obviously, the invention is not restricted 100 to the specific structural details and arrangement and location of parts set forth in connection with the illustrative embodiment thereof, and modifications may be made therein without departing from the spirit 105 and scope of the invention.

Having thus described the invention and its preferred embodiment, that which is claimed as new is:—

1. A boot or shoe outsole comprising a 110 leather sole portion and a heel portion of commercial leatherboard that has been sized and compressed to the final size and form in which it is to be used in a finished shoe.

2. A boot or shoe outsole comprising a 115 leather sole portion and a heel portion of commercial leatherboard that has been cut to shape, surface-sized and compressed to the final size and form in which it is to be used in a finished shoe.

3. A boot or shoe outsole comprising a 120 leather sole portion and a heel portion of commercial leatherboard that has been sized and compressed to final size and form to give it a lateral surface of appreciable depth having improved and modified characteristics rendering it capable of being beaded and finished in a manner comparable to leather.

4. A boot or shoe outsole comprising a 125

leather sole portion and a heel portion of commercial leatherboard that has been cut to shape, surface-sized and compressed to improve and modify its surface characteristics and produce an ultimate surface that may be finished in a manner comparable to leather.

5 5. A boot or shoe outsole comprising a leather sole portion and a randed heel portion of commercial leatherboard that has been sized and compressed to the final size and form in which it is to be used in a finished shoe, said form including a clean-shaped, smooth and durable randing.

10 6. A boot or shoe bottom comprising a short sole of leather, an adjoining heel-seat portion composed of commercial leatherboard that has been sized and compressed to final size and form to give it a smooth, hard and durable lateral surface which is retained in the finished shoe, and a heel of final size and form attached to said heel-seat portion in registry therewith.

15 7. A boot or shoe sole comprising a forepart portion of quality outsole stock, and a complete heel portion of stock of inferior quality attached thereto and forming with the forepart a solid outsole, said heel portion having the fibers of its lateral surface modified and hardened to render said surface ca-

pable of taking a finished comparable to the finish of the quality forepart stock.

20 8. A boot or shoe outsole consisting of a forepart and shank of leather and a heel-seat secured thereto of stock of inferior quality, said heel-seat being surface-sized, cut and compressed thereby having its surface characteristics modified and a hardened edge produced having a surface approximating leather.

25 9. A boot or shoe bottom comprising an outsole composed of a short sole of suitable outsole stock and a heel-seat attached thereto of stock inferior to outsole stock, and a heel of final size and form attached to said outsole, said heel-seat having been surface sized and compressed to final size and form producing a hardened lateral surface capable of taking a finish comparable to that of the adjoining sole and heel surfaces without trimming.

30 10. A boot or shoe sole comprising a forepart portion of suitable outsole stock, and a heel portion of stock of inferior wearing quality that is heel-shaped in plan and has been hardened by both lateral and transverse compression and shaped to a size and form for exact registration with the heel seat of the heel to be used in the finished shoe.

ERASTUS E. WINKLEY.
